UNITED STATES PATENT OFFICE.

JERRY H. HOLLOWAY, OF APPERSON, OKLAHOMA.

GAS REGULATOR AND AUTOMATIC SHUT-OFF.

Application filed April 27, 1923. Serial No. 635,085.

To all whom it may concern:

Be it known that I, JERRY H. HOLLOWAY, a citizen of the United States, residing at Apperson, in the county of Osage and State 5 of Oklahoma, have invented certain new and useful Improvements in Gas Regulators and Automatic Shut-Offs, of which the following is a specification.

The object of this invention is to provide 10 an instrument that will regulate gas pressure.

A further object of the invention is to provide a device of this nature that will close a valve should the gas in the service main be 15 cut off, and will not open when the gas in the service main is turned on until said valve is opened by hand.

A further object of the invention is to provide a device of this nature which is very 20 simple and practical and can be manufactured and sold at a very nominal cost.

The nature and advantages of the invention will be better understood when the following detail description is read in connection with the accompanying drawing forming a part of this application. The invention residing in the construction, combination and arrangement of parts as 25 claimed.

In the accompanying drawing which represents a central cross-sectional view of the invention, partly in elevation the various parts will be referred to by numbers. And, whereas,

1 is a round base. 2 is a housing which is attached to the base 1. 3 is a housing cover which is attached to the housing 2. 4 is the valve operating housing which is attached to the housing 2. 5 is a pipe leading 35 from the service main. 6 is an inlet pipe. 7 is a needle valve of any suitable design. 8 is a bellows support which is attached to the inside of the base 1, as shown. 9 is a bellows which is attached to the support 8.

40 10 is a cover attached to the bellows 9. 11 is a coil spring of suitable design having association with the top of the cover 10 and the plate 12, as shown. 13 is an adjusting screw for the purpose hereinafter described.

45 14 is a bracket attached to the underside of the cover 10. 15 is an outlet pipe. 16 is a butterfly valve arranged in the outlet pipe 15. 17 is an operating lever for the butterfly valve 16. 18 is a connecting rod extending 50 from the lever 17 to the bracket 14. 19

is a lever pivotally attached to the top of the cover 10, as shown. The lever 19 is also pivotally attached to the housing 4, as shown at 20. 21 is a cam which operates the needle valve stem 22. 23 is a rod connecting the lever 19 and the cam 21. 24 is a disk arranged on the needle valve 22 having adjusting nuts above and below, as illustrated. The upper part of the needle valve stem 22 is threaded into the lower part, as illustrated at 25.

In operation, the butterfly is open and practically idle during the normal pressure variations and approaches closed position only when there is an extreme lowering in pressure. The needle valve and the butterfly valve move in opposite directions when they are actuating simultaneously. However, normally the butterfly valve 16 comes into closing action only upon the extreme upward stroke of the needle valve. Thus, when pressure rises within the service main without tripping the regulator, the needle valve will descend as the diaphragm raises to normal conditions, at which time the butterfly valve 16 will normally open. It is therefore obvious that the flow of gas is not stopped entirely but simply placed under control.

Only upon two occasions does the needle valve entirely close. When the gas supply is cut off upon either the intake or the discharge side of the regulator. In the event the said supply is cut off from the intake side, the diaphragm drops down, thereby closing the butterfly valve and opening the needle valve to the extreme top of the stroke thereof, at which time the disc 24 trips out of the cam 21, thus releasing the same, allowing the spring 27 to seat the needle valve. Thus both valves are closed in the absence of flow.

When the gas supply is cut off from the discharge side of the regulator, the back pressure raises the diaphragm until the needle valve closes the butterfly valve being simultaneously operated, thereby cutting off the gas supply from the intake side also. However, immediately upon demand for gas by the discharge side of the regulator, the diaphragm will drop and open the needle valve to allow the required pressure to pass. It will be seen that the said needle valve functions in accordance with the varying pressure of the gas flow.

The butterfly valve has normally only one function. When the gas pressure is sufficiently low to require the needle valve to be fully open, and the diaphragm down to the bottom of the stroke to allow the closed position of the former, to supply the demand; should the pressure in the service main suddenly rise, the results may possibly be disastrous. The butterfly valve is adapted to check or control the pressure of the gas sufficiently to allow only a minimum flow of the latter to pass through the pipe 15, the latter being of such size that the movements of the valve 16 shall not affect the normal flow of gas therethrough during the movement of the bellows regulator.

It is therefore obvious that the present invention contemplates the provision of a regulator which will effectually govern the otherwise varying pressure obtained from a gas main.

What I claim is:

1. A gas regulator of the character described, the combination of a housing, an inlet pipe attached to said housing, an outlet pipe attached to said housing, a bellows disposed in said housing, a valve disposed in said outlet pipe having operatable connection with said bellows, a valve disposed in said inlet pipe having operatable connection with said bellows.

2. An expandible member in association with an accumulating chamber, an inlet pipe attached to said chamber, an outlet pipe attached to said chamber, a valve disposed in said inlet pipe and means for automatically regulating said valve as said expandible member expands and contracts, a valve disposed in said outlet pipe and means for reg-

ulating said valve as the said expandible member expands and contracts.

3. A gas regulator and automatic shut off of the character described, comprising a housing base, a housing mounted thereon, a cover mounted upon said housing, a support arranged inside of said housing base, a bellows mounted upon said support, a cover mounted on said bellows, a coil spring mounted on said bellows cover, an adjusting screw arranged in said housing cover to operate the tension of the aforementioned spring, a bracket arranged on the underside of the aforementioned bellows cover, an outlet pipe arranged on the aforementioned base, a butterfly valve arranged in said outlet pipe, an operating lever attached thereto, a connecting rod between said operating lever and the aforementioned bracket, an inlet pipe arranged in the aforementioned base, a needle valve arranged in said inlet pipe, a lever housing attached to the side of the aforementioned housing, a lever pivotally attached to said lever housing, also pivotally attached to the aforementioned bellows cover, a jawed cam pivotally attached to said lever housing, a connecting rod connecting said cam and the aforementioned lever, a needle valve stem extending from the aforementioned needle valve through the aforementioned lever housing, a disk adjustably arranged on said needle valve stem in the aforementioned lever housing having association with the jaw of the aforementioned jawed cam. As shown and described.

JERRY H. HOLLOWAY.
